UNITED STATES PATENT OFFICE.

SETH WHEELER, OF CASTLETON, NEW YORK.

DELIVERY MECHANISM.

SPECIFICATION forming part of Letters Patent No. 663,057, dated December 4, 1900.

Application filed June 29, 1898. Serial No. 684,737. (No model.)

To all whom it may concern:

Be it known that I, SETH WHEELER, a citizen of the United States of America, and a resident of Castleton, Rensselaer county, New York, have invented certain new and useful Improvements in Delivery Mechanism, of which the following is a specification.

My invention relates to delivery mechanism adapted to deliver articles contained therein either singly or in any predetermined order or quantity; and my invention consists in a receptacle or magazine for containing the articles to be delivered, such magazine having two channels adapted to receive two columns of articles at an angle to each other, a discharge-plate having an orifice corresponding in area with the lower end of one of said channels, means for rotating or partially rotating the discharge-plate relatively to the magazine, a delivery-chute, and a device for guiding the articles to said chute.

My invention may be used by itself as a complete apparatus or may, if desired, be attached to or be a part of a vending-machine.

The objects of my invention are to simplify the construction of such mechanism and reduce the number of working parts to a minimum, at the same time to insure the accurate and positive delivery of the articles singly or in any predetermined order or number; and my invention further consists in certain novel details of construction and combination of parts, as shall hereinafter be more fully set forth.

I will now proceed to describe mechanism embodying my invention with reference to the accompanying drawings and will then point out the novel features in the claim.

In the drawings, Figure 1 is a side elevation, partially in central vertical section, of a machine embodying my invention. Fig. 2 is a front exterior view of same. Fig. 3 is a horizontal transverse section on the line C D of Fig. 1. Fig. 4 is a central section of a discharge-plate employed. Fig. 5 is a face view of same. Fig. 6 is a detail view showing the relative position of two adjacent articles when in different channels in the magazine. Fig. 7 is an edge view of the same.

Similar reference characters designate cor-

responding parts throughout the several figures.

Reference character 1 designates the magazine for containing the articles to be delivered. 2 designates a cap or cover for the same, which is removable for the purpose of obtaining access to the interior of the magazine and which is provided with a lock 4 for securing same in position.

3 is a reinforcing-ring secured to the top of the magazine for the purpose of strengthening same.

8 designates a lower casing or support having feet 9, upon which it stands, and 5 designates a ring or connecting-piece, which supports and to which is secured the magazine 1.

The magazine 1 is provided interiorly with a series of strips 10 of substantially triangular shape in cross-section (see Fig. 3) and which extend clear from the top to the bottom thereof. The disposition of these strips, as shown, forms two channels of equal size within the outer cylindrical casing, in which may be deposited a series of tickets, packages, or other articles. Two of such articles are illustrated in Figs. 6 and 7, in which figures they are also illustrated at the angle relatively to each other that they will be when contained in the said channels.

The articles may be placed each alternately in the two channels, or a plurality may be placed therein alternately, or any number may be so placed in regular or irregular order alternately, or alternately with single articles, as may be so desired, and in such order they will be delivered. I will now describe the means employed for delivering same.

6 designates a supporting-plate. (Shown more particularly in detail in Figs. 4 and 5.) The said plate is mounted in the lower casing or support 8 and adapted to rotate therein. It is provided with a discharge orifice or opening of substantially the area of one of the channels of the magazine, and the said discharge-opening is so arranged relatively to the said channels that upon the rotation of the supporting-plate the said discharge-opening shall alternately register with each of said channels.

11 designates a knob or handle secured to the supporting - plate and by which it is adapted to be operated. The shank of the knob passes through a slot 15 in the lower 5 casing and also through a ring 7, which surrounds the casing and which is thus adapted to rotate with the supporting-plate. The slot 15 limits the movement of the supporting-plate in either direction and is so arranged as to 10 just permit the discharge-opening therein to come into register with each of the channels of the magazine as the plate is moved in one direction or the other. When the said supporting-plate is moved from one side to the 15 other, the lowermost article or articles in the channel with which the discharge - opening registers will fall through the said discharge-opening onto the inclined surface within the lower casing, and thence through the delivery-slot 13.

12 designates a ledge, upon which the article in the channel, which is out of line with the delivery-slot 13, will come in contact in falling. This will have the effect of holding up

one end of the article until the other end has 25 swung around toward the said slot, and thus insure its positive delivery.

14 designates an extending nose or ledge of the delivery-chute, upon which the end of the article to be delivered may rest and from 30 which it may be removed by hand.

What I claim is—

In a delivery apparatus, the combination of a magazine adapted to contain overlapping articles, a rotatable supporting-plate beneath the magazine having a delivery-opening, a chute beneath said plate having a restricted opening, and a device within said chute for engaging articles dropping from the magazine to properly present them to the opening 40 of the chute.

Signed by me at Albany, New York, this 22d day of June, 1898.

SETH WHEELER.
